UNITED STATES PATENT OFFICE

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

SEWING-MACHINE-MOTOR CONTROLLER

Application filed August 3, 1927. Serial No. 210,234.

In the widespread application of electricity to the various arts, the sewing machine has received its share of attention, and various devices for the electric drive and control 5 of sewing machines have been made and used. While the growing demand is for the complete, factory equipped, electric sewing machine, there are in use large numbers of treadle-driven sewing machines which only 10 await the advent of a conveniently applicable and usable form of motor and motor-controller to convert them into electric machines. There has already been provided a sewing machine motor adapted for attachment to the 15 well known family sewing machine so as to become, in effect, a permanent fixture or part of the machine, not requiring to be removed or shifted when the machine is to be put away or made ready for use. I refer to the electric 20 sewing machine described in the U. S. patent to Diehl and Hemleb No. 1,488,234, of March 25, 1924.

The usual sewing machine motor-controllers are of three types, viz., hand-operated, 25 knee-operated, and foot-operated. The hand-operated controller is little used as it interferes more or less with the use of the operator's hands in presenting and guiding the work to the sewing machines. The knee-operated controller is in more general favor, 30 and there is practically no objection to the foot-operated controller in so far as the broad principle of foot-operation is concerned. Foot-controllers, such as heretofore commonly provided, have however been of the 35 portable type comprising a pedal operated rheostat adapted to rest upon the floor adjacent the sewing machine table. The difficulty with this type of foot-controller is that 40 it has a tendency to creep or shift its position. Furthermore, it cannot be placed in a position for convenient operation, for the reason that the treadle-plate element of the 45 sewing machine table occupies the floor space where the foot-controller would be of most convenient access to the operator's foot and where it would be least likely to manifest its creeping tendency.

In the ordinary drop-head sewing machine, 50 as converted to an electric sewing machine

by the application of an electric motor and foot-controller, the treadle mechanism of the sewing machine stand has no function except as a potential foot-power drive and, as above stated, the treadle-plate is in the way of convenient location of the foot-controller. 55

With the idea of using the conveniently accessible and operable treadle-plate as a means for operating the motor-controller, it has been proposed to mount the motor-controller or rheostat on the sewing machine table and connect it by a pull-rod to the treadle-plate, but none of the devices heretofore proposed fills the long-felt want for a treadle-plate operated motor-controller which may 60 be readily applied to or removed from the usual sewing machine table by one not possessed of mechanical skill, and which is of simple and dependable construction and of neat and inconspicuous appearance. 65

The present invention has for an object to provide a motor-controller to fill the want referred to and enable the well-known treadle-driven family sewing machine to be readily converted into an electric machine. 70 75 A further object of the invention is to provide a motor-controller which is readily adaptable for either foot or knee operation. Further objects of the invention will appear from the following description and claims. 80

To the ends in view there is provided a bracket having releasable gripping means adapting it to be firmly secured to the brace member which extends between and joins the legs of the usual cast-iron sewing machine stand. This bracket, when attached to the brace member in question, presents an up-standing base surface upon which the controller unit may be mounted in two different angularly related positions. The controller 85 unit, per se, is of well-known construction embodying a variable resistance unit and a rock-shaft for operating such unit; the mounting provisions being such that the rock-shaft may be disposed horizontally or 90 in an up-and-down position. When disposed horizontally, the rock-shaft may have secured thereto a crank-arm from the free end of which hangs a pitman-section adapted to be 95 connected to the lower section of the usual 100

treadle pitman-rod, for foot operation. When disposed vertically, the rock-shaft may have secured to it a knee-shift lever extending forwardly to a position for convenient knee operation. By mounting the rock-shaft operated controller unit on the brace member of the usual cast-iron sewing machine stand, it is located in a peculiarly advantageous position where it is adaptable for either foot or knee operation with a maximum of convenience and a minimum of appurtenances.

In the accompanying drawings, Fig. 1 is a front side elevation of a sewing machine embodying the invention. Fig. 2 is a sectional view on the line 2—2, Fig. 1. Fig. 3 is a detail view of the upper end of the treadle pitman-rod. Fig. 4 is a detail view of the crank-strap to which the treadle pitman-rod is connected for foot-power operation. Fig. 5 is a detail view of the controller rock-shaft to which the pitman-rod is connected for electrical operation. Fig. 6 is a front elevation of the iron frame-work of a sewing machine stand to which the motor-controller is attached and converted for knee operation. Fig. 7 is a top plan view of the stand shown in Fig. 6. Fig. 8 is a perspective view of the controller converted for foot operation. Fig. 9 is a similar view of the controller as converted for knee operation. Fig. 10 is a top plan view of the variable resistance unit of the controller. Fig. 11 is a side view of the latter with the cover shown in section. Fig. 12 is a section on the line 12—12, Fig. 10, and Fig. 13 is a perspective view of the cover element of the controller.

According to the preferred embodiment of the invention illustration, Fig. 1 represents a well-known family machine of the drop-head type comprising a sewing head 1 seated upon the wooden top 2 carried by the cast-iron frame-work including the end legs 3 and intermediate spacer or brace-member 4. The brace-member 4 has mounted thereon the usual treadle-plate 5 and crank-shaft 6 carrying a belt-wheel 7 which, for foot-power operation, is connected by the belt 8 to the usual grooved balance-wheel 9 of the sewing machine.

The crank-shaft 6 is embraced by the crank-strap 10 which, for foot-power operation, is connected to the usual treadle-rod or pitman 11, as shown in Fig. 6; the crank-strap 10 constituting, in effect, an upper pitman section or extension of the pitman 11. The pitman 11 has the usual ball-and-socket connection at its lower end 12 with the treadle-plate 5 and is threaded at its upper end 13 to screw into the threaded socket 14, Fig. 4, of the crank-strap 10.

For electrical operation, the belt 8 is removed from the balance wheel 9 and a motor 15, such for example as that shown in said Diehl and Hemleb patent is applied to the sewing head and connected by the belt 16 to

the balance-wheel 9. The motor 15 is connected to the source of electrical energy by the supply cord 17 in series with the cord 18 leading to the motor-controller 19 which, in the present instance, is a variable resistance device mounted on the brace-member 4 and including an operating rock-shaft 20 carrying a crank-arm 21 to the apertured free end of which is connected a hook 22 having the threaded socket 23, Fig. 5, for reception of the threaded end 13 of the pitman-rod 11. As thus connected for electrical operation, pressure upon the treadle-plate 5 effects a rocking movement of the controller rock-shaft 20, which effects a variation of the resistance in the motor-circuit and enables the speed of the motor 15 and machine 1 to be nicely controlled.

While the motor-controller 19 may be of any desired type, it is preferred to employ a variable resistance unit such as disclosed in the Patent to D. H. Chason, No. 1,643,292, of September 27, 1927. This variable resistance device comprises a supporting base 24 for a well-known type of compression rheostat, having a porcelain body 25 formed with a pair of wells 26, which are substantially filled with stacks 27 of resistor disks of carbon, graphite, or the like. Terminals 28 are provided at one end of each stack of disks 27 and a terminal pressure head 29 is provided at the opposite end of each of such stacks. Slidably mounted in the porcelain body is the rheostat operating rod 30, one end of which carries the insulating bushing 31 passing through the apertured arm 32 of the bell-crank lever 32, 33 fulcrumed at 34 on the base 24. The rod 30 carries at its other end the leaf-spring bridging contact member 35 and the stiffer backing member 36 which apply the variable working pressures to the carbon disks when the rod 30 is moved endwise. The coil-spring 37 retains the bushing 31 in working engagement with the arm 32 of the bell-crank lever. The operating rock-shaft 20 is journalled in the bearing bushing 38 in the upstanding wall 39 at one end of the base 24 and has fixed to its inner end the cam-plate 40 having the cam-edge 41 in working engagement with the arm 33 of the bell-crank lever. The cam-plate 40 is also formed with stops 42 which limit its rocking motion by engagement with the base 24. The coil-spring 43 urges the cam 40 and rock-shaft 20 to "off" or non-running position. A sheet-metal cover 44 is applied to the base 24 to encase the resistance unit. This cover has retaining lips 45, 46, under-lapping the base 24; there being a fastening screw passed through the lip 46 to hold the cover securely in position.

To mount the controller on the brace-member 4 there is provided an adapter 47, Fig. 8, comprising a plate having a pair of overhanging hooks 49 at its upper edge. Adjustably secured to the adapter 47 by the screw 120

50 is the plate 51 having the under-hanging hook 52; the plate 51 having in it a slot 53 through which the screw 50 passes. The slot 53 is surrounded by a raised rim 54 which tapers in thickness toward the plate 51 from the end nearest the hooks 49. The head of the screw 50 bears upon the rim 54 and, by reason of the tapering thickness of the latter, effectively locks the hook 52 against separation from the hooks 49; such hooks firmly gripping the central horizontal bars 55 of the brace-member. The plate 51 lies between the spaced rests 51' which bear against the rear side of the brace-member when the hook 52 is fastened in clamping position.

15 It will be noted that the base 24 has two threaded screw holes 56, while the adapter plate 47 has two similarly spaced but non-threaded holes 57 through which fastening screws 58 are passed into the base 24 to secure the controller to the adapter plate 47 with its rock-shaft 20 disposed horizontally, Fig. 8. The plate 47 is also preferably provided with a third screw-hole 59, through which 25 and the upper of the screw holes 57, the screws 58 may be passed into the threaded holes 56 in the base 24 to secure the controller in a position turned 90° from its previously described position, or with its rock-shaft 20 disposed in an upstanding position for reception of a knee-shift lever 59 which extends forwardly, Fig. 7, to a position within comfortable reach of the operator's knee.

20 By mounting the controller 19 on the brace-member 4, and particularly at the rear of brace-member 4, it is located in a position particularly advantageous for easy conversion from foot to knee operation and vice versa. It is also located in a position where 40 its connection with the usual treadle pitman-rod may be effected with great simplicity. Still further, it is not in a conspicuous position and, together with its cord 18, is well off of the floor and out of the way.

25 Having thus set forth the nature of the invention, what I claim herein is:—

1. The combination with a sewing machine stand having the usual end legs, intermediate brace-member, belt-wheel, belt-wheel supporting crank-shaft, and treadle, of a motor-controller unit having an operating rock-shaft and means for mounting such unit on and at the rear of such brace-member with said rock-shaft disposed horizontally and extending toward said belt-wheel, a crank-arm on said rock-shaft, and a multi-sectioned pitman, the lower of which is the usual pitman-rod connection to the treadle-plate, and an upper section of which connects said lower 55 section to said controller crank-arm for electrical operation.

2. A sewing machine motor-controller comprising a variable resistance unit, a casing for said unit, separable upper and lower 60 clamping fingers connected to said casing and

adapted to grip the upper and lower horizontal bars of the brace-member of the usual cast-iron sewing machine stand.

3. A convertible foot or knee operated motor-controller comprising a variable resistance unit having an operating rock-shaft, 70 a bracket adapted for mounting on the brace-member of the usual cast-iron sewing machine stand, and means for securing said resistance unit to said bracket in either of two angularly related positions in one of which the rock-shaft is adapted for connection to the treadle-plate of the sewing machine stand and in the other of which the rock-shaft is adapted to carry a knee-shift lever.

80 In testimony whereof, I have signed my name to this specification.

DANIEL H. CHASON.
